ELECTROSTATIC HEATING

Jack E. Duff, Canton, Ohio, assignor to The Hoover Company, North Canton, Ohio, a corporation of Ohio

Application November 24, 1944, Serial No. 564,944

5 Claims. (Cl. 219—19)

1

The present invention relates to apparatus for ironing material and more particularly to an iron and an ironing surface in a high frequency electrostatic field for generating heat to iron material.

An object of the invention is to provide a new and improved iron and ironing surface. Another object is to provide an iron and ironing surface capacitatively coupled in a high frequency electrostatic field. A further object is to provide a capacitatively coupled iron and ironing surface wherein the material to be ironed acts as a dielectric to generate heat for ironing the material. Another object is to provide an iron having a sectional sole plate, each section adapted to form a flux path between the iron and ironing surface. Still another object is to provide an iron having a sectional sole plate adapted to be electrically connected to provide a flux path therebetween, depending upon the temperature of the sole plate. A further object is to provide an iron and ironing surface, the latter having electrodes of such area relative to the area of the sole plate, that the sole plate will span adjacent electrodes to provide a flux path between the electrodes and iron in different operating positions of the iron. Other objects and advantages of the invention will be apparent from the following description and drawings, wherein:

Figure 1 is an elevational view, partly in section, of the ironing surface and iron;

Figure 2 is a bottom plan view of the iron sole plate;

Figure 3 is a top plan view of the ironing surface showing the electrodes, and in dotted lines different positions of the iron;

Figure 4 is a diagrammatic view of the electrical connections when the iron has its thermostat open and is in different positions with respect to the electrodes in the ironing surface, and

Figure 5 is a view similar to Figure 4 but with the thermostat closed.

The embodiment of the invention herein disclosed comprises an elongated ironing support 10 having a frame 11 of wood or other electrical insulating material upon which is mounted a base 12 of porcelain or ceramic or other material to provide an electrical insulator and a poor conductor of heat in a high frequency field.

Mounted on the base 12 are electrodes 13 and 14 in the form of a comb and provided with electrode strips 15 and 16, respectively. The electrode strips 15 and 16 are interdigitated laterally of the base 12 and are seated in corresponding

recesses 17 in the porcelain base 12 and are separated by the projecting walls 18 of each recess 17 to lie flush with the top surface of the porcelain base 12. The top surfaces of the electrodes 15 and 16 on the porcelain base 12 are covered by an ironing pad 50 upon which is placed the material 48 to be ironed.

The electrodes 15 and 16 may be metal foil or sprayed copper and form two plates of a capacitor in the ironing surface of the base 12. The electrodes 15 and 16 are connected through leads 19 and 20 to a high frequency generator 21 which is connected to a source of current. The high frequency generator 21 is balanced to ground and may be of a type which delivers electric current at high frequencies, to provide the adjacent electrode strips 15 and 16 with current of opposite polarity and form an electrostatic field therebetween.

20 The iron 25 comprises a base 26 and a handle 27 both formed of heat and electrical insulating material such as plastic. The base 26 is provided with a front and rear recess spaced apart as at 28, and a metallic sole plate section 29 is 25 molded in the front recess, and another metallic sole plate section 30 is molded in the rear recess so that the metal sole plate sections 29 and 30 and the plastic spacer 28 are in one plane and form the ironing surface of the iron.

30 The front sole plate section 29 is substantially triangular in shape while the rear sole plate section 30 is substantially rectangular. The areas of the sole plate sections 29 and 30 are designed with respect to the areas of the interdigitated electrode strips 15 and 16 in the ironing surface so that in different positions of the iron, the sole plate formed by the sections 29 and 30, will span the adjacent electrodes 15 and 16. The handle 27 of the iron is provided with a hand grip portion 31 and front and rear legs 32 and 33, respectively, the latter having holes 40 through which bolts 34 are threaded into nuts 35 molded into the base 26 to removably attach the handle 27 to the base.

45 A thermostat 36 has a bimetallic strip 37 arranged in an opening 38 in the base 26 and one end 39 of the strip 37 is anchored to the inner surface of the sole plate section 29 and its opposite end is provided with a contact 40 adapted to engage a contact 41 mounted on the inner surface of the sole plate section 30. The contact 40 normally engages the contact 41 on the rear sole plate section 30 and when in this position provides a flux path between the separate sole plate sections 29 and 30, but when the

sole plate rises to a predetermined temperature the bimetallic strip 37 flexes upwardly to the position shown in Figure 1, to interrupt the flux path between the sole plate sections 29 and 30.

The temperature at which the bimetallic strip 37 operates is selectively controlled by means of a rod 42 threaded into a nut 43 molded into a platform 44 extending between the front and rear legs of the handle 27. The rod 42 is adjusted by an indicator knob 45 to alter the spacing of the lower end 46 of the rod 42 with respect to the bimetallic strip 37 to thereby vary the temperatures at which the flux path between the sole plates 29 and 30 will be interrupted. An unshown dial is mounted on the upper surface of the platform 44 and cooperates with the pointer 47 on the knob 45 to indicate the temperature setting of the thermostat 36 at which the latter will operate to interrupt the flux path between the sole plate sections 29 and 30. If desired, the dial may be calibrated for different materials to be ironed to indicate the setting for the particular type of material at which the thermostat will operate to provide the required temperature for ironing.

When the iron 25 is placed upon the base 12, the sole plate sections 29 and 30 in the majority of positions form the third plate in the capacitor system and provide a return path for the electrostatic flux between the adjacent electrodes 15 and 16, while the material 48 being ironed between the sole plate and electrodes acts as a dielectric in the capacitor system and is thereby heated for the ironing operation.

In the ironing operation, the generator 21 is set to provide a frequency which is best suited for the material 48 to be ironed and the thermostat knob 45 is adjusted to the desired temperature. Placing the iron 25 on the material 48 capacitatively couples the sole plate sections 29 and 30 to the underlying electrode strips 15 and 16 of opposite polarity, while the material 48 acts as a dielectric therebetween to thereby generate heat in that part of the material 48 which is beneath the iron as the latter is moved over the electrodes. Thus the dielectric loss in the material 48 being ironed is converted into electrostatic heat for ironing the material.

In Figure 3 is disclosed a variety of positions which the iron 25 might take with respect to the electrode strips 15 and 16 during the ironing operation. Positions A', B', C' and D' in Figure 3 correspond to the positions A, B, C and D of Figures 4 and 5, and show the different flux paths which are dependent upon the position of the iron 25 relative to the electrodes. When the iron 25 is in position A' and the thermostat 36 open, each of the sole plate sections 29 and 30 completely cover an electrode of opposite polarity as shown at A in Figure 4, but since the sole plate sections 29 and 30 do not span adjacent electrodes of opposite polarity, no flux path is provided therebetween, with the result that no heating occurs in the material 48 being ironed. If the thermostat 36 is closed as shown in C' of Figure 3 and at C in Figure 5, the thermostat 36 electrically connects the sole plate sections 29 and 30 to form in effect a unitary sole plate and provides a flux path for the electrostatic field from the electrode 15 through the material 48 into the sole plate section 29, through the bimetallic strip 37 to the sole plate section 30 and thence through the material 48 to the electrode 16. In this position of the iron with the thermostat closed, the maximum possible flux

flows to produce maximum heating in the dielectric material 48 since the total areas of the sole plate sections 29 and 30 are capacitatively coupled over electrodes 15 and 16 of opposite polarity.

If the iron is in the position shown at B' of Figure 3, and at B of Figure 4, each sole plate section 29 and 30 spans adjacent electrodes of opposite polarity and form their own flux path through the material 48, although the thermostat 36 is open, to thereby heat the material 48. Thus each half of the sole plate sections 29 and 30 acts as a return path for the electrostatic flux from each electrode of opposite polarity, and since the areas of the sole plate sections 29 and 30 which are capacitatively coupled with electrodes of opposite polarity are not greatly unbalanced, the heat produced in the material 48 will be relatively close to the maximum. If the thermostat 36 is closed, as indicated at D' in Figure 3 and D in Figure 5, the same quantity of flux flow will be maintained because each half of the sole plate sections 29 and 30 continue to act as a return path for one-half of the electrostatic flux path from each electrode of opposite polarity to thereby continue to heat the material 48.

If the iron is in the position E shown in Figure 3, each half of the lateral widths of the sole plate sections 29 and 30 span electrodes of opposite polarity and provide a flux path to produce maximum heating in the dielectric material 48 being ironed.

When the iron is in the F position, the heating will be at a minimum since the the portions 52 of the sole plate sections 29 and 30 are capacitatively coupled to electrodes 15 of like polarity, and the area of such portions 52 are greatly unbalanced with respect to the area of the portions 53 which are coupled to the electrode 16 of opposite polarity.

In ironing position G, with the thermostat 36 open, each sole plate section 29 and 30 has a relatively small area 54 capacitatively coupled to electrodes of opposite polarity in comparison to the areas of the portions 55, so that each sole plate section is unbalanced over adjacent electrodes of opposite polarity with the result that less heat will be generated in the material 48. If the thermostat 36 is closed, as shown in ironing position H, greater heat will be generated in the material 48 since the thermostat electrically connects the sole plate sections 29 and 30 and the total area of the portions 54 and 55 capacitatively coupled to each electrode is more evenly divided over electrodes of opposite polarity.

Thus the movement of the iron over the material 48 causes a rapid change of flux paths in the sole plate sections 29 and 30, and the intensity of the heat supplied to the material 48 being ironed is varied by such movement of the iron and is dependent upon the relative areas of the sole plate sections which are capacitatively coupled with electrodes of opposite polarity. The thermostat 36 provides means for selectively controlling the ironing temperature by disconnecting the sole plate sections 29 and 30 to thereby interrupt the flux path therebetween and thus reduce the total area of the sole plate which is available to form the return flux path so that the heat applied to the material 48 is reduced.

I claim:

1. An iron for use on an ironing surface having a high frequency field, said iron comprising a body, a sole plate on said body formed in a plu-

rality of spaced separate sections each to carry the flux of the high frequency field during the ironing of material on said surface, and a thermostat for electrically connecting said spaced sole plate sections upon a decrease in temperature below a given value and disconnecting them upon a rise in temperature above a given value whereby the high frequency flux produced by the field will flow between said spaced sole plate sections with low sole plate temperatures and the flow of flux therebetween will be interrupted with high sole plate temperatures and confined to flow in each spaced sole plate section.

2. An iron comprising an electrical insulating body, a sole plate on said body and formed in a plurality of separate sections, means electrically insulating said sections from each other, and a thermostat for electrically connecting said separate sections of said sole plate upon a decrease in temperature below a given value and disconnecting them upon a rise in temperature above a given value.

3. An iron for use on an ironing surface having a plurality of spaced high frequency electrodes, said iron including a sole plate formed of spaced metallic sections and forming the ironing surface of said iron, and thermostatic means for electrically connecting said spaced metallic sole plate sections upon a decrease in temperature below a given value and disconnecting them upon a rise in temperature above a given value whereby high frequency flux produced by the electrodes will flow between said sole plate sections with low sole plate temperatures and the flow of flux will be interrupted with high sole plate temperatures.

4. Ironing apparatus comprising a support for the material to be ironed, a plurality of spaced electrodes in said support for connection to an oscillator, an iron having a sole plate of spaced metallic sections forming the ironing surface of said iron, each of said spaced sole plate sections forming a free electrode capacitively coupled to said electrodes to provide a flux path between adjacent electrodes when said sole plate sections are brought into ironing contact with the material on said support, and thermostatic means for electrically connecting said spaced metallic sole plate sections upon a decrease in temperature below a given value and disconnecting them upon a rise in temperature above a given value whereby high frequency flux pro-

duced by the electrodes will flow between said sole plate sections with low sole plate temperatures and the flow of flux will be interrupted with high sole plate temperatures.

5. An iron for use on an ironing surface having a plurality of spaced high frequency electrodes, said iron including a sole plate formed of spaced sections and forming the ironing surface of said iron, means electrically insulating 10 said spaced sections from each other, each of said spaced insulated sole plate sections being capacitively connected to the electrodes to carry the high frequency flux produced by the electrodes during ironing of material on said surface, and thermostatic means for electrically connecting 15 said spaced sole plate sections upon a decrease in temperature below a given value and disconnecting them upon a rise in temperature above a given value whereby high frequency flux produced by the electrodes will flow between said spaced sole plate sections with low sole plate 20 temperatures and the flux will be interrupted with high sole plate temperatures and confined to flow in each spaced sole plate section.
